[57] CLAIM

The ornamental design for a cooking and utility pan, as
shown.

DESCRIPTION

FIG. 1 is a top plan view of a cooking and utility pan
showing my new design;

FIG. 2 is a side elevational view thereof;

FIG. 3 is a cross-sectional view taken on line 3—3 of
FIG. 1;

FIG. 4 is a top perspective view thereof; and

FIG. 5 is a bottom perspective view thereof.
